US0D1065122S

(12) **United States Design Patent** (10) **Patent No.:** **US D1,065,122 S**
(45) **Date of Patent:** **** Mar. 4, 2025**

(54) **WIRELESS AUDIO RECEIVER**

(71) Applicant: **SHENZHEN GUOYUCHEN TECHNOLOGY CO., LTD.**, Shenzhen (CN)

(72) Inventor: **Liang Jiang**, Shenzhen (CN)

(73) Assignee: **SHENZHEN GUOYUCHEN TECHNOLOGY CO., LTD.**, Shenzhen (CN)

(**) Term: **15 Years**

(21) Appl. No.: **29/852,174**

(22) Filed: **Sep. 2, 2022**

(30) **Foreign Application Priority Data**

Aug. 16, 2022 (CN) 202230535553.2

(57) **CLAIM**

The ornamental design for a wireless audio receiver, as shown and described.

DESCRIPTION

FIG. 1 is a front elevational view of a wireless audio receiver showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a first perspective view thereof shown; and,

FIG. 8 is a second perspective view thereof shown.

Broken lines seen in the drawings depict portions of the wireless audio receiver that form no part of the claimed design.

1 Claim, 6 Drawing Sheets
